CLAIM

The ornamental design for a combined ship mounted oil spill containment boom and mounting plate, as shown and described.

DESCRIPTION

FIG. 1 is a front and top perspective view of the combined ship mounted oil spill containment boom and mounting plate embodying the design of the present invention;

FIG. 2 is a front perspective view thereof in the collapsed configuration;

FIG. 3 is a front elevational view thereof;

FIG. 4 is a rear elevational view thereof;

FIG. 5 is a side elevational view thereof;

FIG. 6 is a side elevational view thereof;

FIG. 7 is a top plan view thereof; and,

FIG. 8 is a bottom view thereof.

FIG.1

FIG. 2

FIG. 3

FIG. 4

FIG. 5

FIG. 6

FIG. 7

FIG. 8
